DESIGN FOR A SHOE OR SIMILAR ARTICLE

David Levin, New York, N. Y.

Application June 30, 1937, Serial No. 70,135

Term of patent 3½ years

To all whom it may concern:

Be it known that I, David Levin, a citizen of the United States of America, residing in city of New York, county of New York, and State of New York, have invented a new, original, and ornamental Design for a Shoe or Similar Article, of which the following is a specification, reference being had to the accompanying drawing, forming part thereof.

Fig. 1 is a plan view of a shoe or similar article showing my new design.

Fig. 2 is a perspective view thereof.

My design is characterized by the punched holes in the insole of shoe as shown, through which upper is pulled through.

I claim:

The ornamental design for a shoe or similar article, substantially as shown and described.

DAVID LEVIN.
